UNITED STATES PATENT OFFICE.

JOHN J. DOYLE, OF NEW YORK, N. Y., ASSIGNOR TO AUTOGRAPHIC TIME LOCK COMPANY, INC., OF BAY SHORE, NEW YORK, A CORPORATION.

AUTOGRAPH TIME-RECORDER FOR LOCKS.

1,099,738.

Specification of Letters Patent.

Patented June 9, 1914.

Application filed June 11, 1913. Serial No. 772,997.

To all whom it may concern:

Be it known that I, JOHN J. DOYLE, a citizen of the United States, and a resident of the city of New York, borough of Manhattan, in the county and State of New York, have invented a new and Improved Autograph Time-Recorder for Locks, of which the following is a full, clear, and exact description.

10 The object of the invention is to provide a new and improved autograph time recorder for locks such as are used on doors and the like, the recorder being arranged to produce a permanent record of the opening and closing of the lock for any given period of time and in such a manner that tampering with the lock during this period is recorded.

In order to accomplish the desired result 20 use is made of a clock-driven drum containing a record sheet, a stylus mounted adjacent the said drum and adapted to mark on said record sheet, and actuating means for the stylus and controlled by a movable member of the lock so that the stylus makes a plurality of lines indicating opening and closing of the lock, and a line approximately at right angles to the said opening and closing lines to indicate the period of time 25 between the opening and closing lines.

A practical embodiment of the invention is represented in the accompanying drawings forming a part of this specification, in which similar characters of reference indicate corresponding parts in all the views.

Figure 1 is a front elevation of the time recorder for locks as applied and with the casing in section; Fig. 2 is a cross section of the same on the line 2-2 of Fig. 1; Fig. 3 40 is an enlarged face view of a portion of the record sheet; Fig. 4 is an inverted sectional plan view of the time lock on the line 4-4 of Fig. 1 and with the parts in position when the lock is unlocked; Fig. 5 is a 45 similar view of the same with the parts in position when the door is locked; Fig. 6 is an inverted sectional plan view of the time lock on the line 6-6 of Fig. 1 and with the parts in position when the door is unlocked; Fig. 7 is a similar view of the same with the parts in position when the door is locked; Fig. 8 is an enlarged side elevation 50 of the stylus, nut and screw rod for moving the stylus lengthwise of the drum, the stylus being in inactive position; Fig. 9 is a simi-

lar view of the same with the stylus in active marking position; and Fig. 10 is a sectional plan view of the same on the line 10-10 of Fig. 8.

On the door A is secured a casing or other support B for the autograph time recorder, and on the said support B is mounted a locking device C of any approved construction, and preferably provided with a key-controlled bolt C' adapted to engage a keeper C' on the door casing A' to lock the door A in closed position. On the support B is journaled the shaft D' of a vertically-disposed drum D having the lower end of its shaft D' coupled to a driven shaft E' of a 70 clockwork E of any approved construction and likewise mounted on the support B. On the peripheral face of the drum D is removably held a record sheet F by the use of suitable clamps D'. The record sheet F is provided with vertical lines F' spaced equal distances apart and representing hours and subdivisions, the numerals F'' indicating the hours being marked on the corresponding hour lines, preferably at the top thereof. 80 As shown, the record sheet indicates twelve hours and the clockwork E rotates the drum D once every twelve hours. The record sheet F is further provided with a spiral line F'', the convolutions of which correspond to those of the screw rod I, which makes one revolution to every revolution of the drum D, so that at each revolution of the screw rod H the stylus G travels a distance corresponding to that between adjacent convolutions of the spiral line F''. In practice, the stylus is set to mark in the space between adjacent convolutions of the spiral line F''. In order to indicate a. m. and p. m. the spiral line 90 is heavy for one convolution and light for the next following convolution, as will be readily understood by reference to the drawings. As shown, the record sheet is arranged for obtaining a week's record of the 100 opening and closing of the locking device C.

On the record sheet F is adapted to indicate a stylus G provided with a shank G' fulcrumed at G' on a lug H' attached to or forming part of a nut H screwing on a screw 105 rod I arranged parallel to the axis of the drum D and journaled in bearings on the support B. The lower end of the screw rod I is provided with a gear wheel J in mesh with a gear wheel J' secured to the bottom 110

of the drum D so that when the latter is rotated by the clockwork E then a like rotary motion is given to the screw rod I to move the nut H and consequently the stylus 5 G lengthwise of the drum D and the record sheet F. The pivot G² for the stylus arm G' is arranged at an angle to the axis of the drum D so that the stylus G swings relatively to the face of the record sheet F, as 10 will be readily understood by reference to Figs. 8 and 9. The swinging movement of the stylus G on the arm H' and in a direction toward the record sheet F is limited, and the back of the stylus shank G' is 15 pressed on by a spring G³ secured to an arm H² projecting rearwardly from the nut H. The rear end of the arm H² is forked and engages a rock arm K journaled on the support B and extending the length of the 20 drum D, and the upper end of the said rock arm K is provided with a crank arm K' having a wrist pin K² engaging a slot L' in a plate cam L attached to the bolt C' to move with the same. The cam slot L' has 25 one end L² parallel with the line of movement of the bolt C and the end L² leads to the rearwardly-curved portion L³ terminating in a forwardly-curved portion L⁴ leading to the other end L⁵ of the slot and 30 which end L⁵ is parallel to the end L².

When the bolt C' is in withdrawn position and the door A is consequently unlocked then the wrist pin K² extends in the end L² of the cam slot L', as plainly indicated in Fig. 6, and while the wrist pin K² is in this position the rock arm K holds the arm H², nut H, arm H' and stylus G in the position shown in Fig. 4, that is, with the stylus G out of contact with the record sheet 35 F. When the bolt C' is shot out into engagement with the keeper C² to lock the door A in closed position then the cam plate L moving with the bolt C' causes the wrist pin K² to travel in the curved portion L³ of the cam slot L' whereby a rocking movement 40 is given to the rock arm K to swing the arm H², nut H, arm H' and stylus G into the position shown in Fig. 5, to move the stylus in contact with the record sheet F at the same 45 time swinging the stylus G to the right against the tension of its spring G³ on the arm H' to cause the stylus G to make a vertical line F⁴ on the record sheet F (see Fig. 3). When the wrist pin K² finally passes 50 through the portion L⁴ of the cam slot L' then a return movement is given to the stylus G a distance about half way of the end of the movement previously made for the line F⁴, to mark a line F⁵ on the record sheet F. 55 When the pin K² finally reaches the end L⁵ of the slot at the time the bolt C' is completely shot out into engagement with the keeper C² then the stylus G remains in contact with the record sheet F and as the latter is rotated with the drum D a line F⁶ is 60

made on the record sheet at approximately right angles to the closing lines F⁵, F⁴ previously mentioned. When the bolt C is retracted then the plate cam L imparts movement to the stylus G in a reverse direction 70 as previously explained, that is, the stylus makes two approximately vertical lines F⁷, F⁸ on the record sheet F approximately at a right angle to the time line F⁶ marked on the sheet and indicating the time when the bolt was moved into closed position until 75 the bolt was moved into retracted position. When the pin K² reaches the portion L² of the slot L' then the stylus G is again out of engagement with the record sheet F, and 80 during the time the bolt is in retracted position no line is marked on the record sheet F, but when the bolt is again moved into closed position then another set of lines F⁴, F⁵, only in reverse direction, are marked on 85 the record sheet F. Thus the empty space between the line F⁸ and the next closing line F⁴ indicates the length of time which elapses during the time the bolt was in retracted position. 90

Presuming that a person surreptitiously opens the bolt C' to gain entrance to the room to which the door A leads, then opening lines F⁷, F⁸ are marked on the record sheet F at the correct time, and even if the person is aware of the arrangement and immediately shoots out the bolt C' after the door A is opened, then another set of closing lines are marked on the sheet. When the person leaves the room and in quick succession moves the bolt C' into open position, closes the door and then shoots out the bolt C' then another set of opening and closing lines F⁷, F⁸ and F⁴, F⁵ are marked on the sheet. In practice such lines will be so close 100 together as to overlie each other owing to the fact that the traveling movement of the record sheet F is very slow, but still the vertical lines indicate the time the person entered the room and the time when the person left the room. In case the person after 105 opening the door B does not shoot out the bolt C' but leaves the same in retracted position, then only the opening lines F⁴, F⁵ are marked on the sheet, and when the door 110 is again closed the closing lines F⁷, F⁸ are marked on the sheet with a blank space intervening between the said sets of lines, thus indicating the length of time the person had been in the room. From the foregoing it 115 will be seen that in either case the record made by the stylus G on the record sheet F discloses the time of entrance and the time of exit. 120

As the stylus G only presses lines on the record sheet F it is evident that the latter is not liable to be torn or mutilated.

The time recorder for locks shown and described is comparatively simple in construction and is not liable to get out of order. 130

Having thus described my invention, I claim as new and desire to secure by Letters Patent:

1. In a time recorder for locks, the combination of a locking device, a clock-driven drum provided with a record sheet, a stylus movably mounted adjacent the said drum and adapted to move in and out of contact with the said record sheet, and actuating means connecting a movable member of the said locking device with the said stylus to move the latter into and out of contact with the said record sheet and to move the stylus at an angle to the direction of the travel of the record sheet and while in contact with the record sheet the said actuating means having devices for holding said stylus in contact with the record sheet to mark a line thereon during the time the locking device is in closed position, the stylus being held out of contact with the record sheet during the time the locking device is open and the stylus making a cross check mark on each end of the line marked on the record sheet on opening or closing the locking device.

2. In a time recorder for locks, the combination of a locking device, a clock-driven drum provided with a record sheet, a stylus movably mounted adjacent the said drum and adapted to move in and out of contact with the said record sheet, and actuating means connecting a movable member of the said locking device with the said stylus to move the latter into and out of contact with the said record sheet and to impart a compound bodily movement to the said stylus while in contact with the said record sheet, the said actuating means having devices for holding said stylus in contact with the record sheet to mark a line thereon during the time the locking device is in closed position, the stylus being held out of contact with the record sheet during the time the locking device is open and the stylus making a cross check mark on each end of the line marked on the record sheet on opening or closing the locking device.

3. In a time recorder for locks, the combination of a locking device having a bolt, a clock-driven drum provided with a record sheet, a screw rod driven from the said drum and extending parallel thereto, a nut screwing on the said screw rod and provided with an arm, a spring-pressed stylus adapted to mark on the said record sheet and pivoted on the said nut to swing obliquely relative to the face of the said record sheet, a rock arm engaging the said nut arm and provided with a crank arm and a plate cam moving with the said bolt and provided with a cam-slot engaged by the wrist pin of the said crank arm.

4. In a time recorder for locks, the combination

of a record sheet, means to cause the said sheet to travel in one direction, a stylus adapted to indicate on the said record sheet, a locking device, and means connecting the said locking device with the said stylus to move the latter into engagement with the record sheet on closing the locking device and to mark closing lines onto the record sheet at an angle to the direction of travel of the record sheet, and to mark a time line on the record sheet in the direction of the travel of the record sheet, the said stylus on opening the locking device marking a set of opening lines on the said record sheet at an angle to the direction of the travel of the record sheet and to move the stylus out of contact with the record sheet.

5. The combination of a locking device and a time recorder controlled by a movable member of the locking device, the said time recorder including a clock-driven drum provided with a record sheet, and a stylus adapted to move into and out of engagement with the said record sheet on moving the said movable member, the said actuating means having devices for holding said stylus in contact with the record sheet to mark a line thereon during the time the locking device is in closed position, the stylus being held out of contact with the record sheet during the time the locking device is open and the stylus making a cross check mark on each end of the line marked on the record sheet on opening or closing the locking device.

6. In combination, a locking device having a bolt, a cam on the bolt, a clock-driven drum provided with a record sheet, a spring-pressed stylus adapted to mark on the said record sheet, the said stylus being pivoted to swing obliquely relative to the face of the said record sheet, and actuating means connecting the said stylus with the said cam to move the said stylus into and out of contact with the said record sheet on moving the bolt into closed or open position, said actuating means having devices for holding said stylus in contact with the record sheet to mark a line thereon during the time the locking device is in closed position, the stylus being held out of contact with the record sheet during the time the locking device is open and the stylus making a cross check mark on each end of the line marked on the record sheet on opening or closing the locking device.

In testimony whereof I have signed my name to this specification in the presence of two subscribing witnesses.

JOHN J. DOYLE.
